UNITED STATES PATENT OFFICE.

THEODORE A. WILLARD, OF CLEVELAND, OHIO, ASSIGNOR TO WILLARD STORAGE BATTERY COMPANY, OF CLEVELAND, OHIO, A CORPORATION OF WEST VIRGINIA.

CONNECTOR AND CONNECTION FOR STORAGE BATTERIES.

1,225,297.

Specification of Letters Patent.

Patented May 8, 1917.

Application filed July 16, 1915. Serial No. 40,188.

To all whom it may concern:

Be it known that I, THEODORE A. WILLARD, a citizen of the United States, residing at Cleveland, in the county of Cuyahoga 5 and State of Ohio, have invented a certain new and useful Improvement in Connectors and Connections for Storage Batteries, of which the following is a full, clear, and exact description.

10 This invention relates to a terminal connector and connection for storage batteries, and has for its chief object to provide a construction which overcomes many of the disadvantages of prior tapered plug connections employed heretofore on storage batteries. This application is a continuation 15 of and covers a modification of a somewhat similar construction constituting the subject matter of a companion application Serial 20 No. 40,189 filed by me of even date here-with.

One of the more specific objects of the invention is to provide a connection which is inexpensive, strong, compact and durable, 25 and wherein the coöperating parts, including the battery connector, have low resistance and have such contacting area and are held together so firmly that the connection or joint has low resistance and acid is prevented from creeping between the contacting 30 surfaces. A further object is to provide a connection having a minimum height and which can be easily assembled or taken apart.

35 A still further object is to provide a connection having the above mentioned characteristics wherein the main contacting terminal members are or may be formed of sheet metal punchings.

40 The above and other objects are attained by my invention, which may be briefly summarized as consisting in certain novel details of construction and combinations and arrangements of parts which will be described in the specification and set forth in 45 the appended claims.

In the accompanying sheet of drawings, 50 Figure 1 is a top plan view of a portion of the battery equipped with my improved connector and connection; Fig. 2 is a sectional view through the several parts of the connection; Fig. 3 is a view showing the main parts disconnected; and Fig. 4 is a view similar to Fig. 2 showing a modification.

Referring now to the drawings, 10 represents a battery jar, and 11 a battery terminal or connector which is preferably formed of lead or lead alloy. This connector has a body portion provided with a socket which receives the usual terminal post 11^a projecting up through the cover of the battery and lead-burned to the post. The connector is provided with a lateral extension 12 projecting from the body of the connector near the 60 cover and offset or displaced vertically from the top of the connector. Embedded in this connector is an insert 13 of relatively hard good current conducting material, such as copper or brass. This insert, which is preferably formed of a sheet metal punching, 65 extends through the extension 12 into the body portion of the connector, where it is provided with a portion in the form of an annulus extending about the socket and post. At its other end the insert is provided with a conical boss or head 14 threaded on the interior and projecting through the top of the lateral extension 12.

The other main coöperating part of the 20 connection consists of a terminal 15 of a flexible electric conductor 16, this terminal being also formed from a sheet metal stamping or punching of good conducting material, such as copper or brass, and being 85 provided near its end with an internally and externally tapered head or boss 17, the taper of which coincides with the taper of the part 14 of the insert.

The tapered projection 17 of the terminal 90 15 fits down onto the outer tapered surface of the part 14 of the insert, as shown in Fig. 2, and these coöperating tapered parts are clamped very tightly together by a screw 18 provided with a threaded shank which 95 engages in the threaded opening of the tapered part of the insert and in the preferred construction with a head having an interiorly tapered flange 19 which fits down onto the exteriorly tapered projection 17 of 100 the terminal 15. This flange is inclined or tapered in conformity with the taper of the other two parts so that the three elements 14, 17 and 19 are nested, so to speak, and there is a good area of contact between each pair 105 of engaging parts.

In Fig. 4 I have shown a modification which is of the ~~same~~ construction as that shown in the preceding figures, except the clamping screw here designated 20 is pro-

vided with a plain head without the flange 19, and the part which engages the outer tapered surface of the tapered portion 17 of the conductor terminal is in the form of a 5 separate piece consisting of a clamped washer having inner and outer tapered surfaces.

The tapered part of the insert which projects from the connector, the terminal 15, the washer 21 of Fig. 4, and all of the clamping screw except the threaded shank, will 10 be coated with lead so that these parts will not be corroded by acid. This may be done by plating, or the lead may be cast onto the parts. The coating is indicated in Figs. 2, 15 3 and 4, and is designated 22.

When the screw is tightened the tapered part of the terminal 15 is clamped very tightly between the other two tapered parts with the result that an exceedingly tight 20 joint is provided which has very low electrical resistance and the surfaces of the co-operating parts are so firmly clamped together that acid will not creep between the surfaces so as to corrode them. In consequence, the parts can be easily disassembled 25 when desired and will not stick as has been the case with most of the tapered plug connectors used heretofore.

Additionally, the construction while very 30 efficient from mechanical and electrical standpoints, is inexpensive in view of the low cost of the insert 13 and conductor terminal 15, and the rapidity with which they may be stamped out and formed into shape. 35 A still further important advantage resides in the low overall height of the connection as a whole, this being due to the nesting or telescoping action of the parts, and the fact that the tapered part of the insert projects 40 from the extension 12 which is below the top of the connector 11. It may be mentioned also that the construction admits of the terminal 15 being pointed or turned in any direction with respect to the battery 45 terminal 11.

Having thus described my invention, what I claim is:—

1. A battery connector comprising a body having an insert of relatively hard material, 50 said insert being composed of a sheet metal stamping provided with a tapered part projecting from the connector.

2. A battery connector comprising a body having a lateral extension, a sheet metal 55 insert of relatively hard material in said extension and provided with a tapered terminal portion.

3. A battery connector comprising a body having a socket for a terminal post and having a relatively hard sheet metal insert 60 with a portion extending about the socket and a tapered portion projecting from the connector and adapted to be attached to a conductor terminal.

4. A connection adapted particularly for 65 storage batteries comprising a battery terminal having an insert of relatively hard material with a part projecting from the terminal, a conductor terminal having a tapered portion which engages the projecting part 70 of the insert, and clamping means for fastening the parts together and provided with a portion tapered which fits onto the tapered part of the conductor terminal.

5. A connection adapted for storage 75 batteries comprising a battery terminal having a tapered part; a conductor terminal having a part with tapered surfaces, one tapered surface engaging the tapered part of the battery terminal; and clamping means having a tapered surface fitting onto another 80 tapered surface of the conductor terminal.

6. In a connection for storage batteries, 85 a connector having an insert composed of sheet metal stamping provided with a tapered part, a conductor terminal formed from sheet metal and having a tapered part, and a threaded clamping member for drawing the tapered parts together.

7. In a connection for storage batteries, 90 a connector having an insert composed of sheet metal stamping provided with a tapered part projecting from the connector, a conductor terminal formed from sheet metal and having a tapered part engaging 95 said tapered part of the insert, clamping means for drawing the tapered parts together, and including a member having a tapered portion which engages the exterior of one of said tapered parts. 100

8. A connection for storage batteries, comprising a battery connector or terminal having a lateral extension, an insert of relatively hard material in said extension provided with a tapered part projecting therefrom, a conductor terminal having a tapered part which engages the tapered projecting part of the insert, a threaded clamping member for drawing said tapered parts together, said insert and said terminal of the conductor being stamped from sheet metal. 110

In testimony whereof, I hereunto affix my signature.

THEODORE A. WILLARD.
